UNITED STATES PATENT OFFICE.

OSWALD PAUL ERNEST WOLF AND BENJAMIN HEWITT, OF MATHESON, ONTARIO,
CANADA.

ROPE-CLIMBING APPARATUS.

Application filed April 11, 1927, Serial No. 182,928, and in Canada July 17, 1926.

Our invention is characterized by a rope climbing apparatus which comprises an elongated sleeve, consisting of two hinged parts and a rope grip within the sleeve 5 actuated by a lever fulcrumed intermediate its ends to the sleeve. The lever, exterior of the sleeve, is attached to a stirrup strap or bar having at its lower end a stirrup in which the foot of the climber is entered, and 10 a slotted brace is pivoted to the sleeve and to the stirrup strap for maintaining the latter in substantially parallel relation to the sleeve.

The rope is entered between the rope grip 15 and the wall of the sleeve, and when weight is imposed on the stirrup strap and lever the rope grip binds the rope against the wall of the sleeve and the climbing apparatus is then prevented from moving in either direction on the rope, but when the weight is removed from the stirrup strap and lever, the sleeve can move in either direction on the rope.

For an understanding of the invention 25 reference is to be had to the following description and accompanying drawings, in which:

Fig. 1 is a perspective view of the apparatus,

Fig. 2 is a sectional elevational view showing in full lines the position of the rope grip when weight is imposed upon the stirrup strap and lever, and in dotted lines, the 30 position of the parts when the apparatus is free to move in either direction upon the rope,

Fig. 3 is a perspective view of the stirrup, and

Fig. 4 is a rear view of the apparatus 40 showing the hinge connection for the sleeve sections.

Like characters of reference refer to like parts throughout the specification and drawings.

1 represents a tube or sleeve, the bore 22 of which is of corresponding dimensions to the rope. In the preferred construction, the sleeve consists of two parts 1^a, 1^b, connected together, at one side of the sleeve, by hinges 2, so that they can be opened to permit of the sleeve being placed on the rope. At the 50 other side of the sleeve, each of the parts 1^a, 1^b, is formed with a lug or flange 3 and

the sleeve parts and lugs are separated to provide a slot 1^c lengthwise of the sleeve. Entered through the slot is a lever 4 mounted interjacent its ends on a fulcrum 5 which extends through the lugs 3, the fulcrum 5 shown in the drawings consisting of a bolt which serves to secure the parts together in their closed position. One arm 4^a of the lever projects within the sleeve and the other arm 4^b projects outside of it. The arm 4^a is provided with a rope grip 6 and the arm 4^b is forked. Entered between the forks of the arm 4^b is the upper end of a stirrup strap or bar 8 and passing through the forks of the arm 4^b and the stirrup strap 8 is a bolt 9 by which the stirrup strap or bar is connected to the arm 4^b. Attached to the outer surface of the sleeve and spaced from it is a plate 10 and entered through the plate and adjacent side of the sleeve is a bolt 10^a. Pivoted on the bolt 10^a between the plate and sleeve is a link 11 and this link 65 is pivotally connected to the stirrup strap 8 and operates to brace and maintain the stirrup strap substantially parallel with the sleeve during the performance of its functions. At the lower end of the stirrup strap 70 is a stirrup 12 for the foot. The weight of the stirrup strap and stirrup is sufficient to draw the lever arm 4^b downward and raise the lever arm 4^a and rope grip. The latter then engages the rope and binds it against 75 the sleeve with sufficient pressure to prevent the sleeve moving in either direction on the rope.

When the weight of the user is imposed upon the stirrup strap the pressure of the 80 grip against the rope is increased to an extent that makes it impossible for the sleeve to move in any direction.

It is usual to employ two climbing apparatus on a single rope or to employ two 85 ropes with a climbing apparatus on each. By removing the weight alternately from the stirrup strap, of each climbing apparatus, and raising it until its respective grip is disengaged from the rope, its sleeve can be 90 stepped either up or down the rope. The stirrup strap of the other climbing apparatus at this period carries the full weight 95 of the user. In this way each apparatus can be moved step by step in either direction 100 along the rope until the limit of travel is 105

attained, but there can be no movement of the sleeve on the rope until the stirrup strap is relieved of the weight on it and is moved upward to release the pressure of the grip 5 on the rope.

Where two climbing apparatus are used on the same rope, one sleeve is arranged above the other, and in that case it is necessary to make the stirrup strap of one apparatus 10 longer than that of the other, the difference of the lengths of the stirrup straps compensating for the difference in the elevation of the two sleeves on the rope.

Having thus fully described our invention, what we claim as new and desire to secure by Letters Patent is:

1. A climbing apparatus comprising a sleeve, a lever fulcrumed to the sleeve interjacent its ends, one arm of which is entered within the sleeve and the other arm of which projects outside of it, a rope grip actuated by the lever arm within the sleeve, a stirrup strap attached to the lever arm projecting outside the sleeve, a stirrup 25 for the stirrup strap, and a slotted brace connected to the sleeve and to the stirrup strap.

2. A rope climbing apparatus comprising an elongated sleeve consisting of two hinged 30 parts and means for locking them together, a lever fulcrumed to the sleeve having one arm entered within the sleeve and provided with a rope grip and the other arm projecting beyond it, a stirrup strap connected 35 to the lever arm projecting beyond the sleeve, a stirrup for the stirrup strap, and a slotted

brace pivoted to the stirrup strap and to the sleeve.

3. A rope climbing apparatus comprising an elongated sleeve consisting of two parts 40 connected together at one side of the sleeve by hinges and at the other side of the sleeve formed with lugs through which is entered a bolt to secure the parts together in their closed position, a lever fulcrumed on the 45 bolt, one arm of which is entered within the sleeve and provided with a rope grip and the other arm of which is forked and projects outside of the sleeve, a stirrup strap attached to the forked end of the lever, and a 50 stirrup for the stirrup strap.

4. A rope climbing apparatus comprising an elongated sleeve consisting of two parts 55 connected together at one side of the sleeve by hinges and at the other side of the sleeve formed with lugs through which is entered a bolt to secure the parts together in their closed position, a lever fulcrumed on the 60 bolt, one arm of which is entered within the sleeve and provided with a rope grip and the other arm of which is forked and projects outside of the sleeve, a stirrup strap attached to the forked end of the lever, a 65 stirrup for the stirrup strap, and a slotted brace pivotally connected to the stirrup strap and to the sleeve.

Dated at the town of Matheson, in the district of Cochrane, and Province of Ontario, Dominion of Canada, this 26th day of Feby., 70 1927.
